APPARATUS FOR AND METHOD OF TREATING THE BRIMS OF HATS

John E. Kane and Fred R. Olsen, Danbury, Conn.,
assignors to The Frank H. Lee Company, Danbury, Conn., a corporation of Connecticut

Application February 24, 1940, Serial No. 320,624

19 Claims. (Cl. 223—7)

This invention relates to apparatus for and a method of treating the brims of hats, and in regard to its more specific aspects, to apparatus for and method of mellowing or rendering pliable the brims of hats following completion of the finishing operations practiced thereon.

In the manufacture of hats, and particularly fur felt hats commonly referred to as soft hats, it is customary in a preliminary operation to treat the hat with a stiffening solution throughout an area which subsequently forms the hat brim. Such a solution generally incorporates shellac or like resinous material which is taken up by the hat body. Following drying, the shellac hardens and imparts a degree of stiffness to the treated brim portions. In subsequent operations, the hat is heated and thereupon cooled, as for example, when the brim is flanged in a final finishing operation. The heating of the hat brim during flanging causes the previously hardened shellac or like stiffening agent to become softened, with subsequent cooling acting to reharden the shellac which thereupon assists in setting of the brim to the shape imparted to it in the flanging operation.

Due to rehardening of the shellac under conditions different than those encountered in the first drying, or due possibly to the fact that the hat body originally took up an excess amount of the stiffening solution, the hat brim, following flanging, is in many cases unduly stiff and non-pliable, and in the case of turned up, as distinguished from snap-brim hats, this undue stiffness of the brim may result in brim distortion in wear or may even cause discomfort to the wearer. It is therefore desirable that the hat brim be treated in such manner as to remove excess and/or undesirable stiffness, such treatment being known in the trade as "mellowing."

The present invention contemplates and has for one of its objects the provision of improved and simplified apparatus for working the brims of hats following the finishing thereof in such manner as to render them mellow and pliable; the provision of a hat brim mellowing apparatus as aforesaid by which the working of the brim can be adjusted as desired to handle brims of different widths and thicknesses; the provision of a hat brim mellowing apparatus requiring no particular skill in its operation and by which the desired mellowing treatment can be effected in one or more passes of the brim therethrough; the provision of hat brim mellowing apparatus which is certain in its operation, which is characterized by rugged and durable construction and

which is constituted by a minimum of working parts requiring little or no attention of repair; and the provision of an improved method of working the brims of hats following the flanging or finishing operations conventionally formed thereon, for the purpose of imparting to the brim the requisite and desirable properties of mellow ness and pliability.

Other objects will be in part obvious and in part hereinafter pointed out in connection with the following analysis of this invention wherein is illustrated an embodiment of the invention in detail.

In the drawings—
15 Fig. 1 is a vertical section along the longitudinal center line of apparatus in accordance with the present invention.

Fig. 2 is a section taken along lines 2—2 of Fig. 1;

20 Fig. 3 is a plan view of the apparatus illustrated in Figs. 1 and 2;

Figs. 4 and 5 are sectional details illustrating the undulatory brim pass provided by apparatus as in the foregoing;

25 Fig. 6 is a separated view of the upper and under brim working elements.

Referring to the drawings wherein like reference characters indicate like parts throughout the several views, reference character 10 indicates a horizontally disposed hat supporting surface in the nature of a table, being supported by a suitable framework which may be comprised by the several vertical legs 12, 13 and 14 and cross beams 15, the framework also supporting 30 a motor shelf 16 disposed below the table. The table 10 is provided with a through opening 20 which may be of arcuate contour, as indicated in Fig. 3, and provides a mounting for spaced, vertical posts 21, 22 each secured in fixed relation 35 to the table 10 as by spaced securing nuts 23, 24. Preferably, the posts are each threaded to receive a locating nut 25 which serves to locate at an appropriate level above the table a cross bar 26 which extends between the posts and is held 40 in position on the locating nuts by the handled or winged nuts 28.

Secured to the cross bar as by lag screws 30 and depending therefrom is an upper brim treating element 32 in the nature of a block to be 45 more specifically described, said block terminating generally in the plane of the working surface of table 10 and being disposed over the table opening 20.

Disposed in cooperating relation with the upper brim treating element 32 is an under brim

treating element 34, also in the nature of a block. The block 34 extends upwardly through the table opening 20, being carried at the upper end of a connecting rod 35 to be described more fully hereinafter.

The block 32, which is adapted to contact the upper face of a brim, is preferably formed to extend in plan along an arc which corresponds generally to the oval shape or contour of a hat and has a relatively front vertical face 38 against which the crown of a hat may be disposed, said face thus serving to properly locate a hat on the table 10 so that its brim may extend between blocks 32, 34.

The relatively rear face of the block 32 is provided with a plurality of vertical flutes or teeth 40, four such flutes being shown for purposes of illustration as in Fig. 6. By reference to Fig. 1, the flutes 40 when viewed in vertical section curve under the block and extend relatively forwardly along a curvature which corresponds generally to the flange or curl of a hat brim. Also, by reference to Figs. 1 and 2, it will be seen that the depth of the flutes 40 decreases as they progress under the block; or, conversely, the depth of the flutes increases with brim width.

The under block 34, which is roughly L-shaped in vertical section and which in plan extends along an arc corresponding generally to the oval of a hat, has formed on its relatively front concave face a plurality of vertically extending flutes or teeth 42, as more clearly indicated in Fig. 6. The flutes 42, shown as three in number, are arranged to complement and/or mesh with the flutes 40 of the upper block 32, the flutes 42 preferably having appreciable depth throughout their length and bending forwardly beneath block 32 along a curvature corresponding generally to the flange or curl of a hat brim.

As will be apparent from Fig. 1, flutes 42 at their upper end extend into the space between the flutes 40 of the upper block 32 to the depth of about $\frac{1}{2}$ inch, this depth of extension decreasing as the flutes progress downwardly due to the decreasing depth of the flutes 40 as they curve under block 32. Adjacent their lower ends the depth of the flutes 42 is also progressively decreased somewhat with the result that there is provided between the forward portions of the blocks a space of the order of $\frac{3}{8}$ inch when the under block 34 is in its "low" position and, with a $\frac{1}{4}$ inch throw of the under block, a space of the order of $\frac{1}{2}$ inch when the under block is in its "up" position. This spacing between the blocks and the flutes thereof progressively decreases as the flutes extend rearwardly and upwardly of the blocks until the flutes mesh with each other, thus to provide a brim pass which is definitely undulatory in contour along the zone of the edge of the brim of a hat inserted into the space between said blocks.

The arrangement and spacing between the blocks and the flutes thereof is diagrammatically illustrated in Figs. 4 and 5, wherein Fig. 4 is a transverse section through the blocks with the under block in its low position. It will be appreciated that the space between blocks provides a brim pass into which the brim B of a hat can readily be inserted. In Fig. 5 the under block is shown in its up position, in which the space between blocks and flutes thereof is decreased and in which the intermeshing relation of the flutes causes the brim to be undulated.

According to the present invention, the under block 34 is "jigged" or given limited and high

speed reciprocatory movement through its connection with a driving motor 45 operating at about 1800 R. P. M. and being fixedly secured to the motor shelf 15. Shaft 46 of the motor has secured thereto a fly-wheel or equivalent inertia mass 47 from which extends an eccentrically disposed crank 48 operating in a bearing cup or head 50, into which is threaded the lower end of the connecting rod 35 previously referred to. The connecting rod extends through a cylindrical slide bearing 51 trunnioned in a bearing supporting ring or collar 52 held to the table or framework therefor by arms 53.

By the above described arrangements high-speed operation of the motor results in limited reciprocatory or jigging movement of the under block 34 as carried by the connecting rod 35, and the under block 34 is actuated at relatively high speed toward and away from the relatively fixed upper block 32.

The position of the upper block 32 may be varied to accommodate brims of varying weights and/or thicknesses by unthreading the hand nuts 28 and properly adjusting the level of the locating nuts 25 on the bar supporting posts 21, 22, thereby to raise or lower the relatively fixed upper block 32.

In operation, a hat whose brim is to be mellowed is positioned on the table 10 and its brim moved relatively rearwardly into the brim pass between upper and under blocks 32, 34, respectively, to the depth determined by engagement of the hat crown against the vertical front face 38 of the upper block 32, such serving to locate properly the hat for brim treatment.

The hat brim B as partially indicated in Fig. 3 is, in the apparatus illustrated, manually fed through the brim pass whereby successive portions of the brim are worked by the fluted blocks. Such feed movement requires that the hat be turned gradually on substantially the vertical axis of its crown, this requirement being practically satisfied by the provision of the vertical face 38 on block 32, against which the operator may push the crown of the hat whose brim is being worked, as he grasps the hat brim on both sides of the block assembly and feeds the hat therethrough.

With the hat brim extending into the brim pass and feeding therebetween, the flutes of the blocks exert a kneading action on the brim and cause successive portions of the brim to be alternately undulated, the depth or amplitude of the undulations varying from substantially zero (see Fig. 4) to a predetermined maximum (see Fig. 5) and back to zero again, as represented by the up and return travel of the under block for each cycle of its movement. This kneading or undulating of the brim acts to break down and/or rearrange the hardened shellac or equivalent stiffening material of the brim, and the brim is accordingly mellowed and rendered pliable.

In the case of an unduly stiff brim, or where an extra-pliable brim is required, the feed of the brim through the treating blocks may be slowed down as determined by the experience of the operator, or the brim may be given more than one pass through the apparatus.

By reason of the fact that the flutes 40 of the upper block increase in depth as they progress outwardly or radially of the brim being treated, the brim is undulated to a greater extent in the region of its edge or periphery than in its region adjacent the crown. This is desirable for ob-

vious reasons, among which may be noted the requirement for more pliability adjacent the edge of a hat brim rather than adjacent the crown where head size and contour is to be preserved.

As the under block 34, by reason of its mounting directly on the connecting rod, moves in a vertically elongated elliptical path, rather than a truly straight-line path, it has a slight lateral component of movement which of course accentuates the brim kneading action over that obtainable with straight-line movement. Accordingly the mounting of block 34 directly on the connecting rod is of advantage in this respect in addition to the simplification in construction and elimination in parts otherwise necessary.

As many changes could be made in carrying out the above constructions without departing from the scope of the invention, it is intended that all matter contained in the above description or shown in the accompanying drawings shall be interpreted as illustrative and not in a limiting sense.

We claim:

1. A hat brim mellowing machine comprising brim engaging elements having opposed surfaces providing an undulatory brim pass therebetween, said surfaces being each arranged on a curvature corresponding both to the oval of a hat and the flange of the brim thereof, and means for imparting jiggling movement to one of said elements.

2. A hat brim mellowing machine comprising brim engaging elements having opposed surfaces providing an undulatory brim pass therebetween, said surfaces being each arranged on a curvature corresponding both to the oval of a hat and the flange of the brim thereof, means stationarily mounting one of said elements, and means for imparting jiggling movement to the other of said elements.

3. A hat brim mellowing machine comprising brim engaging elements having opposed surfaces providing an undulatory brim pass therebetween, said surfaces being each arranged on a curvature corresponding both to the oval of a hat and the flange of the brim thereof, one of said elements having means for locating a hat so that its brim may extend an appropriate distance into the brim pass, and means for imparting jiggling movement to the other of said elements.

4. A hat brim mellowing machine comprising brim engaging elements having opposed surfaces providing an undulatory brim pass therebetween, said surfaces being each arranged on a curvature corresponding both to the oval of a hat and the flange of the brim thereof, one of said elements having a surface engageable by the crown of a hat whose brim extends into the brim pass, thereby to limit the extent of insertion of the brim into the brim pass, and means for imparting jiggling movement to the other of said elements.

5. A hat brim mellowing machine comprising brim engaging elements having opposed surfaces providing an undulatory brim pass therebetween, the brim engaging surfaces of said elements being arranged on a curvature corresponding both to the oval of the hat and the flange of the brim thereof, means for adjusting the position of one of said elements with reference to that of its complementary element whereby to accommodate hat brims of varying weights and/or thicknesses, and means for imparting jiggling movement to the other of said elements.

6. A hat brim mellowing machine comprising

upper and under elements adapted to engage respectively the upper and under faces of a hat brim, the adjacent surfaces of said elements being complementally fluted to provide an undulatory brim pass, the flutes being arranged on a curvature corresponding both to the oval of a hat and the flange of the brim thereof, and means for imparting limited reciprocatory movement to one of said elements.

10 7. A hat brim mellowing machine comprising upper and under elements adapted to engage respectively the upper and under faces of a hat brim, the adjacent surfaces of said elements being complementally fluted to provide an undulatory brim pass, the flutes being arranged on a curvature corresponding both to the oval of a hat and the flange of the brim thereof, means for providing a fixed mounting for the upper element, and means for imparting limited reciprocatory movement to the under element.

15 8. A hat brim mellowing machine comprising upper and under elements adapted to engage respectively the upper and under faces of a hat brim, the adjacent surfaces of said elements being complementally fluted to provide an undulatory brim pass, the flutes being arranged on a curvature corresponding both to the oval of a hat and the flange of the brim thereof, means adjustably mounting said upper element in fixed position, and means for imparting limited reciprocatory movement to the under element.

20 9. A hat brim mellowing machine comprising upper and under elements adapted to engage respectively the upper and under faces of a hat brim, the adjacent surfaces of said elements being complementally fluted to provide an undulatory brim pass, the flutes being arranged on a curvature corresponding both to the oval of a hat and the flange of the brim thereof, the upper element having a surface engageable by the crown of a hat whose brim extends into the brim pass, means providing a fixed mounting for the upper element, and means for imparting limited reciprocatory movement to the under element.

25 10. A hat brim mellowing machine comprising upper and under fluted blocks disposed to engage respectively the upper and under face of a hat brim, the flutes of one block being disposed intermediate the flutes of the other block, whereby said blocks provide an undulatory brim pass, the flutes of said blocks extending along a curvature corresponding both to the oval of a hat and the flange of the brim thereof, means providing a fixed mounting for one of said blocks, and means for imparting limited reciprocatory movement to the other block.

30 11. A hat brim mellowing machine comprising upper and under fluted blocks disposed to engage respectively the upper and under faces of a hat brim, the flutes of one block being disposed intermediate the flutes of the other block, whereby said blocks provide an undulatory brim pass, the flutes of said blocks extending along a curvature corresponding both to the oval of a hat and the flange of the brim thereof, means providing a fixed mounting for the upper block, and means for imparting limited reciprocatory movement to the under block.

35 12. A hat brim mellowing machine comprising upper and under fluted blocks disposed to engage respectively the upper and under faces of a hat brim, the flutes of one block being disposed intermediate the flutes of the other block, whereby said blocks provide an undulatory brim pass, the flutes of said blocks extending along a curvature

corresponding both to the oval of a hat and the flange of the brim thereof, means adjustably mounting the upper block in relatively fixed position, and means for imparting limited reciprocatory movement to the under block.

13. A hat brim mellowing machine comprising upper and under fluted blocks disposed to engage respectively the upper and under faces of a hat brim, the flutes of one block being disposed intermediate the flutes of the other block, whereby said blocks provide an undulatory brim pass, the flutes of said blocks extending along a curvature corresponding both to the oval of a hat and the flange of the brim thereof, the upper block having a surface engageable by the crown of a hat whose brim extends into the brim pass, means providing a fixed mounting for said upper block, and means for imparting limited reciprocatory movement to the under block.

14. A hat mellowing machine comprising a table providing a hat supporting surface, and having an opening therein, an upper block, means mounting said block from the table, an under block operative through the table opening, the adjacent surfaces of said blocks being complementally fluted, the flutes of one block being disposed intermediate the flutes of the other block, thereby to provide an undulatory brim pass for the brim of a hat supported on said table, the flutes of said blocks being arranged on a curvature corresponding both to the oval of a hat and to the flange of the brim, and means for imparting limited reciprocatory movement to the lower block.

15. A hat mellowing machine comprising a table providing a hat supporting surface, and having an opening therein, an upper block, means mounting said block from the table, an under block operative through the table opening, the adjacent surfaces of said blocks being complementally fluted, the flutes of one block being disposed intermediate the flutes of the other blocks, thereby to provide an undulatory brim pass for the brim of a hat supported on said table, the flutes of said blocks being arranged on a curvature corresponding both to the oval of a hat and to the flange of the brim, a con-

necting rod carrying at its upper end the under block, rotary driving means, and a drive connection between the driving means and the lower end of the connecting rod operative to impart limited reciprocatory movement to the connecting rod and hence to the under block.

16. The method of mellowing the brim of a hat which consists in subjecting successive portions of the brim to the action of opposed surfaces providing an undulatory brim pass thereby to subject the brim to undulations, and simultaneously therewith vibrating or jiggling one of said surfaces thereby alternately increasing and decreasing the depth of the undulations.

17. The method of mellowing the brim of a hat which consists in subjecting successive portions of the brim to the action of elements relatively movable toward and away from each other and provided with complemental surfaces forming an undulatory brim pass thereby to subject the brim to undulations, and simultaneously therewith imparting relative movement to said elements thereby to alternately increase and decrease the depth of the undulations.

18. The method of mellowing the brim of a hat which consists in disposing the brim between complementally fluted surfaces which are arranged on a curvature corresponding both to the oval of the hat and to the flange of the brim thereof and which provide an undulatory brim pass, and simultaneously jiggling one of said surfaces and feeding the brim through the brim pass.

19. The method of mellowing the brim of a hat which consists in disposing the brim between complementally fluted surfaces which are arranged on a curvature corresponding both to the oval of the hat and to the flange of the brim and which are so spaced as to provide an undulatory brim pass whose undulations increase in depth with the width of the brim, jiggling one of said surfaces, and feeding successive portions of the brim through the brim pass thereby to subject the brim to the action of said surfaces.
